(57) **CLAIM**

The ornamental design for a protection device against accidental contact for an electric busbar, as shown and described.

DESCRIPTION

FIG. 1 is a top view of an embodiment of the protection device against accidental contact for an electric busbar;
FIG. 2 is a rear view thereof;
FIG. 3 is a front view thereof;
FIG. 4 is a left side view thereof;
FIG. 5 is a right side view thereof;
FIG. 6 is a bottom view thereof; and,
FIG. 7 is a top left perspective view thereof.

The broken line portion of the drawings is included to show portions of the article and forms no part of the claimed design.
